CLAIM

The ornamental design for a wireless switch, as shown and described.

DESCRIPTION

FIG. 1 is a first perspective of the wireless switch, showing my new design.

FIG. 2 is a second perspective view thereof.

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The back view of the wireless switch is omitted, because it is not visible during normal use.

1 Claim, 7 Drawing Sheets
